UNITED STATES PATENT OFFICE.

EUGEN SCHMIDT, OF ST. PETERSBURG, RUSSIA.

APPARATUS FOR PRODUCING A MIXTURE OF STEAM AND COMBUSTION-GASES.

No. 845,128.

Specification of Letters Patent.

Patented Feb. 26, 1907.

Application filed September 5, 1905. Serial No 277,099.

To all whom it may concern:

Be it known that I, EUGEN SCHMIDT, engineer, a citizen of the Russian Empire, residing at St. Petersburg, in the Russian Empire, have invented certain new and useful Improvements in Apparatus for Producing a Mixture of Steam and Combustion-Gases; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to an apparatus for continuously producing in a closed chamber a mixture of combustion-gases and steam suitable for driving motors, such mixture being, if desired, supplied with a quantity of air under pressure in excess of that required for the combustion of the liquid fuel employed. Apparatus for producing such a mixture are well known, but are generally of a complicated nature and are therefore liable to get out of order, while an apparatus constructed in accordance with the present invention may be constituted of an ordinary steam-boiler having a large water-space.

In the accompanying drawings, Figure 1 is a longitudinal vertical section of an apparatus embodying my invention. Fig. 2 is a vertical cross-section on the line 2 2, Fig. 1, and Fig. 3 shows in cross-section several forms of the distributing-pipe.

Referring more specifically to the drawings, 1 designates a horizontal hermetically-closed cylindrical vessel in which is mounted a combustion-chamber 19, preferably arranged eccentrically near the bottom of said vessel. This chamber has end walls 20 and 21, each provided with a central opening 23, surrounded by a pipe 27, which can be hermetically closed by means of slides 22 or the like, said chamber being provided in its top with an upward-projecting dome 24, having a comparatively small opening 26, normally closed by a flap-valve 25 or any other suitable form of check-valve.

Liquid fuel is sprayed into the combustion-chamber 19 through a nozzle 3, fed from a pipe 14, which latter leads from a supply-tank 12. Compressed air is supplied to the fuel-spray from a compressed-air tank 13 by means of a pipe 29, the inward extension 30 of which has upwardly-directed nozzles 4,

through which the compressed air is made to impinge upon the fuel-spray. An air-pump 15 is provided for forcing compressed air through a pipe 15' into the tank 13, which communicates with the fuel-tank 12 by means of a pipe 17, having a valve 18. If desired, the fuel-tank is connected also with the water tank or tanks 11 by means of branch pipes 17'. The vessel 1 is provided with a dome having a discharge-pipe 5 for the produced mixture of gas and steam, a thermometer 6, and a pressure-gage 7. Regulating devices 9 16, hereinafter more particularly described, are provided, by means of which valves 32 on water-pipes 10 are regulated according to variations in the temperature in the vessel 1.

In the water-pipes a pressure as uniform as possible is maintained and which is higher than that in the vessel 1, which is regulated by a safety-valve 8. On the feed-pipes 10, 14, and 29 there are provided, in addition to the shut-off cocks, non-return valves of any kind, (not shown,) which prevent the contents of the vessel 1 from passing back to the tanks 11, 12, and 13 in the event of the pressure in the latter sinking below a certain degree.

The apparatus as described can be started when there is very little or no water at all in the vessel 1 and also when no compressed air is available, this being effected in the following manner:

The pipe 27 leading from opening 23 in the wall 21 is connected in any suitable manner with a chimney. (Not shown.) The slides 22 in each pipe 27 are opened and naphtha or other liquid combustible is forced by any suitable means, such as a hand-pump, through the spraying-nozzle 3, and the spray is ignited. The resulting flame, which is maintained by air drawn in by the draft, soon heats the combustion-chamber 19 to a high degree. Spraying-nozzles 2 on the ends of the pipes 10, projecting through the end walls of the vessel 1 above the combustion-chamber 19, are then put in action, and the entering water-spray from these nozzles in striking upon the highly-heated upper part of the chamber 19 is at once converted into steam. When the steam in the vessel 1 has attained a certain pressure, it may be employed for working the air-pump 15, which forces air through the vessel 13 into the naphtha-tank 12 and also into the water-tanks 11. The two slides 22 are then

closed, and compressed air is forced through the nozzles 4 into the combustion-chamber 19, which is now closed against the atmosphere. As the pressure in the chamber 19 increases rapidly, the valve 25 is forced open automatically by the gases, which in passing into the vessel 1 come into intimate contact with the steam and water sprays and in imparting heat thereto produce a gaseous mixture at a high pressure, which passes off through the discharge-opening 5 in the dome. The ascending combustion-gases and the resulting mixture of steam and gases on its way to the discharge-opening 5 passes through one or more wire-gauze partitions 28 or the like arranged in the dome, by means of which the gaseous mixture is freed from soot and other solid particles before passing away. This gaseous mixture being now made to act upon the air-pump 15 effects an increased production of compressed air and raises the pressure in the air-tank and the naphtha and water tanks to the requisite high degree.

If during the working the combustible and air supplies are effected under constant pressure, the supply thereof will increase when the pressure in the vessel 1 decreases, and by this means the pressure in the vessel 1 will be rapidly raised to the normal degree again.

If, on the other hand, the pressure in the vessel 1 increases beyond the normal, less combustible will enter in a given time, and thus reduction of pressure in the vessel 1 to the normal will also be effected. With a constant pressure in the air, water, and fuel vessels an automatic regulation of the pressure of the produced gaseous mixture will be effected when the consumption thereof is more or less variable, the regulation being effected by variation of composition of the gaseous mixture.

In order to maintain the gaseous mixture below a certain admissible maximum temperature in case of sudden and considerable fluctuations in the consumption, the regulating devices 9 16 may be employed in addition, by means of which on the increase of the temperature of the gaseous mixture the water-supply is automatically increased and, on the other hand, is decreased when the temperature falls. This regulating device consists of a metal tube 9, fixed to the end wall of the vessel 1, and through the open outer end of the tube passes a metal rod or tube 16, having its inner end fixed to the inner end of tube 9, while the outer end is attached to a lever 31 of the regulating-valve 32 on the pipe 10. The rod 16 being made of a metal having an expansion coefficient different from that of the metal of the tube 9 it will be seen that the variations in temperature within the vessel 1 will produce a corresponding outward or inward motion of the rod 16, such that with a decrease of temperature it will effect an increased closing of the supply-

valve, while with an increase of temperature in the vessel 1 it will effect a greater opening of the valve.

Any water that is not evaporated flows down over the outside of the chamber 19, collects in the bottom of the vessel 1, and is drawn off from time to time. It is, however, possible, without interfering with the rapid generation of steam by the direct contact of the water-spray with the heated top surface of the chamber 19, to allow the water to accumulate in the lower part of the vessel 1 until it rises to about half the height of the chamber 19. The water-level could, however, be allowed to rise to a height indicated by the dotted line A B, Figs. 1 and 2, and not only chamber 19 but also the check-valve 25 are completely under water. In this case the apparatus may be started and, if desired, worked as an ordinary steam-boiler, the slides 22 being opened and the pipe 27 in the end wall 21 connected to a flue-pipe, while liquid-fuel spray is introduced through the nozzle 3 and ignited.

When sufficient steam-pressure has been generated, both slides 22 may be closed. Air under pressure is then forced in through pipe 29 30, and the gaseous mixture thus produced when at sufficient pressure forces itself through the valve or valves 25 and through the layer of water above them and mixes with steam in the vessel. In order to maintain the variations of temperature within certain limits with such a high-water level in the case of sudden considerable fluctuations in the consumption of the gaseous mixture without the automatic regulating devices 9 16 or the like, there may be arranged round the combustion-chamber 19 two or more check-valves or sets of check-valves, such as 25. These valves are loaded by springs, counterweights, or the like, in such manner that the valves situated at a lower level are generally kept closed and only open when, in consequence of a sudden decrease of pressure in the steam-chamber, a large quantity of combustion-gases have to be discharged into the same.

A second check-valve 33, loaded by a spring 36 and located at one of the lowermost points of the combustion-chamber, is shown in addition to the above-mentioned non-return valve 25. The hot gases escaping through this valve 33 are forced into the water-space of the vessel 1 through a distributing-pipe 24, having a plurality of small apertures 35 in its bottom wall. With this arrangement a portion of the hot combustion-gases have in case of a sudden decrease of pressure in the vessel 1 to pass through a considerable height of water column into the steam or gas space, as indicated by the arrows a, Fig. 2. Becoming highly saturated with steam, they become correspondingly cooled. The reestablishment of the normal

pressure is in this case not effected as rapidly as with the arrangement of a single dome 24 with valve 25; but, on the other hand, the temperature of the gaseous mixture will not 5 rise to the same extent as before, and with an unequal consumption of the gaseous mixture this can always be produced in such manner that its temperature never exceeds a certain limit.

10 If desired, suitable means, such as the regulating device 9 16, may be provided, which only operate at a high temperature within the apparatus and then cause an additional water-spray to be directly admitted 15 into the upper part or steam-chamber of the vessel 1 through a suitably-arranged nozzle. (Not shown.)

I claim—

1. In an apparatus of the character described, the combination with a closed vessel, of a combustion-chamber mounted therein, a nozzle adapted to direct a spray of fuel longitudinally of the combustion-chamber, a plurality of nozzles adapted to direct streams 25 of air transversely of the path of the fuel, a valved port in the bottom of the combustion-chamber to establish communication between the combustion-chamber and the vessel, and means to inject water into the latter 30 to cover the combustion-chamber.

2. In an apparatus of the character described, the combination with a closed vessel, of a combustion-chamber therein, a nozzle adapted to inject a spray of fuel longitudinally of the combustion-chamber, a plurality of nozzles adapted to direct streams of air transversely of the path of the fuel, valved 35 ports in the top and bottom of the combustion-chamber near the end opposite the fuel-nozzle to establish communication between 40

the combustion-chamber and vessel, and means to supply water into the latter to cover the combustion-chamber.

3. In an apparatus of the character described, the combination with a closed vessel, of a combustion-chamber mounted therein, a nozzle adapted to inject a spray of fuel longitudinally of the combustion-chamber, a plurality of nozzles adapted to direct streams 45 of air transversely of the path of the fuel, a valved port in the top of the combustion-chamber near the end opposite the fuel-nozzle to establish communication between the combustion-chamber and vessel, a plurality of nozzles in the latter adapted to spray water 50 therein, and a valved port in the bottom of the combustion-chamber.

4. In an apparatus of the character described, the combination with a closed vessel, of a combustion-chamber mounted therein, a nozzle adapted to inject a spray of fuel longitudinally of the combustion-chamber, a plurality of nozzles adapted to direct streams 55 of air transversely of the path of the fuel, a valved port in the top of the combustion-chamber near the end opposite the fuel-nozzle; to establish communication between the combustion-chamber and vessel, means to inject water in the latter, a valved port in the bottom of the combustion-chamber, and a 60 perforated distributing-pipe communicating with the latter port.

In testimony that I claim the foregoing as my invention I have signed my name in presence of two subscribing witnesses.

EUGEN SCHMIDT.
